UNITED STATES PATENT OFFICE

2,425,093

AMPULE CUTTER

David W. Fosler, Indianapolis, Ind.

Application May 6, 1944, Serial No. 534,406

2 Claims. (Cl. 49—52)

1

The present invention relates to an ampule cutter, and the primary object of the invention is to provide an instrument, simple in construction, substantially automatic in operation, and substantially fool-proof, which can be used quickly by a physician to make the necessary score mark upon the neck of an ampule, or the like, to provide for a clean, sure break when the sealed end of the ampule is removed by the physician. Of course, the instrument has other uses, since it may be used for scoring or cutting any kind of element which is receivable in its hook; but it is primarily designed for the above purpose.

A further object of the invention is to provide an instrument of the character described which will not be in any way damaged by long hours in a steam sterilizer, or any other type of sterilizing device, and which is so constructed as to guard, to a considerable extent, against contamination or the arising of septic conditions in those portions of the instrument intended to contact the ampule.

To the accomplishment of the above and related objects, my invention may be embodied in the form illustrated in the accompanying drawings, attention being called to the fact, however, that the drawings are illustrative only, and that change may be made in the specific construction illustrated and described, so long as the scope of the appended claims is not violated.

Fig. 1 is a side elevation of an instrument constructed in accordance with my invention, parts being shown in section for clarity of illustration;

Fig. 2 is an enlarged fragmental elevation of the forward end of the plunger forming a part of the present invention, the tip thereof being shown in section;

Fig. 3 is a corresponding view of the plunger, taken at right angles to the plane of Fig. 2;

Fig. 4 is a view similar to Fig. 1 but showing a modified form of the invention; and

Fig. 5 is an elevation of the instrument of Fig. 4, viewed from the right of Fig. 4.

Referring more particularly to the drawings, it will be seen that my instrument comprises a barrel or body 10 carrying, at one end, a hook 11 formed to provide an angular recess 12 defined by walls 13 and 14, the angular interval between which is less than 90° for a reason which will appear. I consider 84° to be the ideal angle included between the walls 13 and 14.

Reciprocably mounted in the barrel 10 is a plunger 15 urged by a spring 16 within said barrel toward the recess 12. A plug 17 is threadedly received in the lower end of the barrel 10 and acts as an abutment for the spring 16.

2

The barrel 10 is formed with a longitudinal slot 18 through which projects the stem 19 of a thumb button 20, said stem 19 being threadedly engaged in a suitable transverse bore in the plunger 15. At its outer extremity, the plunger 15 carries a diamond 21.

It will be seen that, if the barrel 10 is held in the operator's hand, the button 20 can readily be engaged by the operator's thumb to retract the plunger 15 against the tendency of the spring 16. Now the neck of an ampule can be entered in the hook 11, through the open side thereof, and placed in the recess 12. If the plunger 15 is now released, the spring 16 will move the plunger 15 upwardly until the diamond 21 engages the neck of the ampule to hold the same in the recess 12. If the ampule is now rotated about its long axis, the diamond 21 will score the external surface of the ampule sharply and cleanly so that the ampule neck can be broken off smoothly.

I have found, by actual experimentation that, if the angle included between the walls 13 and 14 is as large as 90°, the ampule will not be retained steadily in the recess 12, but will shift, in one direction or the other, along the wall 13 or 14, during rotation, depending upon the direction of rotation. Thus if the angle included between the wall 13 and the axis of the plunger is as large as 45°, rotation of an ampule in a counterclockwise direction, as viewed in Fig. 1, while held in the recess by the spring-pressed plunger, will tend to cause the ampule to be cammed downwardly along the wall 13, against the resistance of the spring 16, whereby the ampule is moved

out of proper cooperative relation with the diamond 21. If the maximum lateral distance between the wall 13 and the plunger 15 is as large as, or greater than, the diameter of an ampule neck being scored, that tendency will cause the ampule to be moved entirely out of cooperative relation with the diamond, and to be caught between the plunger and the adjacent walls of the hook. Such an occurrence may frequently result in damage to, or breakage of, the ampule.

On the other hand, I have found that if the angle included between the walls 13 and 14 is substantially less than 90°, and particularly if the maximum lateral distance between the wall 13 and the plunger 15 is less than the diameter of an ampule neck being scored, the ampule neck is retained steadily and solidly in the recess 12. I now believe an angle of 84° to be optimum; and preferably the axis of the plunger will bisect the angle included between the walls 13 and 14.

It is to be noted that the hook 11 lies in a plane

including the axis of the body 10, and that the slot 18 likewise lies in that plane and on the side of the body adjacent the free end of the hook. As a consequence, when a user of my cutter takes the tool in hand for use, it falls naturally into a position in which the button 20 and the open side of the hook face the user, whereby the axis of an ampule or the like to be cut is directed into a substantially horizontal position transverse to the user. In other words, the location of the slot 10 and the thumb piece 20 in the illustrated relation is calculated to result in maximum convenience for the user of the instrument.

The manner of securing the diamond 21 in place in the end of the plunger 15 is an important feature of the present invention. I have found, in actual practice, that unless the diamond is set with considerable care and with due regard for the conditions under which the instrument will be used, it is likely to become loose, in which case the score line made upon the article to be cut will not be smooth and clean; and crevices will be opened between the diamond and its setting, permitting foreign matter to be retained, and creating an aseptic condition. The formation of any crevice is particularly undesirable in an instrument which is to be thrown into a steam sterilizer, since moisture will enter the crevice and may very possibly produce corrosion which, of course, will exaggerate the crevice and the undesirable conditions resultant therefrom.

After considerable experimentation, I have found what I now consider to be the optimum means of mounting the diamond 21. The end of the plunger 15 is formed with a socket or cavity 24, preferably in the form of a truncated pyramid having a plane or part-cylindrical floor. The diamond 21 selected for use will preferably have a substantially wedge shaped edge 22, as will be clear from an inspection of Figs. 2 and 3; and its base 23 will preferably be larger, in all dimensions, than its outer end. The cavity 24 will be packed with silver-solder, and the base of the diamond will be buried in the mass of silver-solder, leaving only a small portion of the outer end of the diamond projecting beyond the plane including the thin peripheral lips of the cavity. Now, the lips of the cavity will be spun or otherwise turned inwardly, as indicated at 26, to overlie the mass of silver-solder 25, and preferably to come into actual engagement with the body of the diamond 21 about its entire perimeter. Because of the funnel shape of the cavity 25, the terminal portions of the cavity lips will be very thin and flexible, so that they can be worked readily into intimate engagement with the entire perimeter of that portion of the diamond located at the surface of the mass of silver-solder 25. Thereafter, the completed end of the plunger is brought to a temperature of about 1200° F., whereby the mass of silver-solder is, in effect, "welded" to the shaped lips of the cavity to produce a complete and permanent seal about the diamond.

I have found that this form of setting very satisfactorily provides a firm and permanent mounting for the diamond, and that, over long periods of relatively rough use and repeated sterilizations of the instrument, the diamond does not become loosened, and crevices do not form about its perimeter.

The instrument thus far described is intended for the physician to carry with him for instant use wherever he may be. In his office, or in clinics, laboratories, hospitals, and the like, it will be desirable to mount such an instrument permanently so that it will always be available to any worker, and will not be inadvertently carried away. To that end, I may provide for the instrument above described a mounting bracket 10 indicated generally at 27 and to which the barrel 10 of the instrument will preferably be soldered or welded, or otherwise permanently secured. Said bracket is formed to provide a pair of feet 28 and 29 adjacent the midpoint of the slot 18, and a third foot 30 projecting beyond the rearward end of the barrel, said feet being perforated to receive fastening screws 31, 31 which may be set into a vertical or horizontal wall, cabinet, or table surface, thus permanently mounting the instrument for use.

I am aware of the existence of the expired patent to Francisco Foz Bello No. 1,584,572; but for reasons which will be apparent from the above disclosure, the present invention constitutes an improvement over the disclosure of that patent, involving the novel features recited in the appended claims.

I claim as my invention:

1. An instrument for perimetral scoring 30 glassware and the like comprising a tubular body, a spring-pressed glass-cutting plunger axially reciprocably mounted in said body and axially projecting at one end therefrom, a retaining hook 35 fixedly associated with said body at said end and formed to define a first portion having a wall inclined away from the axis of said body and in the direction of projection of said end, a second portion having a wall joined to said first wall and inclined toward the axis of said body in 40 the direction of projection of said end and meeting said axis in an angle less than 43°, and a third portion having a wall joined to said second wall substantially at its intersection with said body axis, said third wall being inclined outwardly 45 from said axis but toward said body at an angle less than 43° to said axis, and terminating in a free end spaced from said body.

2. The instrument of claim 1 in which said hook portions define a common plane and said body is formed with an axially extending slot disposed in said plane, and a thumb button fixed to said plunger and projecting through said slot for manual manipulation of said plunger.
